(57) **CLAIM**

The ornamental design for a flooring panel with multiple veneer segments as shown and described.

DESCRIPTION

FIG. 1 is a perspective view of a flooring panel with multiple veneer segments in accordance with a first embodiment of my design;

FIG. 2 is a front elevational view of the flooring panel with multiple veneer segments of FIG. 1;

FIG. 3 is a left side elevational view of the flooring panel with multiple veneer segments of FIG. 1;

FIG. 4 is a right side elevational view of the flooring panel with multiple veneer segments of FIG. 1;

FIG. 5 is a bottom plan view of the flooring panel with multiple veneer segments of FIG. 1;

FIG. 6 is a top plan view of the flooring panel with multiple veneer segments of FIG. 1;

FIG. 7 is an enlarged view of the bottom plan view of FIG. 5;

FIG. 8 is an enlarged view of the top plan view of FIG. 6;

FIG. 9 is an enlarged detail left side view of a middle portion of the flooring panel with multiple veneer segments of FIG. 1, taken in the detail circle indicated in FIG. 3;

FIG. 10 is a perspective view of a flooring panel with multiple veneer segments in accordance with a second embodiment of my design;

FIG. 11 is a front elevational view of the flooring panel with multiple veneer segments of FIG. 10;

FIG. 12 is a left side elevational view of the flooring panel with multiple veneer segments of FIG. 10;

FIG. 13 is a right side elevational view of the flooring panel with multiple veneer segments of FIG. 10;

FIG. 14 is a bottom plan view of the flooring panel with multiple veneer segments of FIG. 10;

FIG. 15 is a top plan view of the flooring panel with multiple veneer segments of FIG. 10;

FIG. 16 is an enlarged view of the bottom plan view of FIG. 14;

FIG. 17 is an enlarged view of the top plan view of FIG. 15;

(Continued)

FIG. 18 is an enlarged detail left side view of a middle portion of the flooring panel with multiple veneer segments of FIG. 10, taken in the detail circle indicated in FIG. 12; FIG. 19 is a perspective view of a flooring panel with multiple veneer segments in accordance with a third embodiment of my design; FIG. 20 is a front elevational view of the flooring panel with multiple veneer segments of FIG. 19; FIG. 21 is a left side elevational view of the flooring panel with multiple veneer segments of FIG. 19; FIG. 22 is a right side elevational view of the flooring panel with multiple veneer segments of FIG. 19; FIG. 23 is a bottom plan view of the flooring panel with multiple veneer segments of FIG. 19; FIG. 24 is a top plan view of the flooring panel with multiple veneer segments of FIG. 19; FIG. 25 is an enlarged view of the bottom plan view of FIG. 23; FIG. 26 is an enlarged view of the top plan view of FIG. 24; and, FIG. 27 is an enlarged detail left side view of a middle portion of the flooring panel with multiple veneer segments of FIG. 19, taken in the detail circle indicated in FIG. 21. The broken lines having consistent dash lengths (dash-dash-dash) represent portions of the flooring panel with multiple veneer segments that form no part of the claimed design. The dot-dash broken lines represent boundaries of the enlarged views and form no part of the claimed design. There are symbolic breaks along the lengths of the flooring elements of FIGS. 19-22. In these figures, the break lines and the open spaces between the break lines form no part of the claimed design.
